UNITED STATES PATENT OFFICE.

CARL E. ZETLITZ, OF CHICAGO, ILLINOIS.

FASTENER.

Application filed June 4, 1921. Serial No. 475,059.

To all whom it may concern:

Be it known that I, CARL E. ZETLITZ, a citizen of the United States, and a resident of Chicago, in the county of Cook and State 5 of Illinois, have invented certain new and useful Improvements in Fasteners, of which the following is a full, clear, and exact description.

The invention relates to collar clips. The 10 object of the invention is to provide an improved clip for securing a collar so that it will not slip over the shirt band and which will space the inner and outer portions of the collar from one another, so that a tie 15 may be easily adjusted through the collar.

The invention consists in the several novel features hereinafter set forth and more particularly defined by claim at the conclusion hereof.

20 In the drawings: Fig. 1 is a side elevation of a device embodying the invention, a portion of a shirt and a collar being shown in section. Fig. 2 is a perspective of the improved clip. Fig. 3 is a section taken on 25 line 3—3 of Fig. 1.

The improved clip is formed of a strip of metal bent to form a downwardly extending inner member 4, an intermediate member 5 and an outer member 6. Members 4 30 and 5 are adapted to fit against and engage the inner and outer surfaces of the band 7 of a shirt 8. The looped connecting portion 9 between members 4 and 5 extend over and around the upper margin of the band 7, 35 so that said members will be pressed together to clamp the shirt band between them. The outer member 6 is connected to the intermediate member 5 by a loop 10 which is resilient and will press the outer member to- 40 wards the intermediate member 5, so that the band or inner portion 11 of a collar 12 will be clamped between the intermediate member 5 and the outer member 6. The outer member 6 is curved transversely, as at 13, 45 and has its upper end 14 extended to space the collar 12 from the band 11 so that a neck-

tie between the band 11 and collar 12 will not be gripped in the collar and may be easily adjusted and slipped through the collar in forming the tie. 50

The invention exemplifies a clip which is formed of a single piece of metal and which is provided with members for gripping the collar and shirt bands so that the collar will not slip over the shirt band or the shirt 55 band from working out under the collar. Also a clip which secures the collar on the shirt and spaces the collar band from the collar to prevent the necktie from being pinched in the collar. 60

The invention is not to be understood as restricted to the detail set forth, since these may be modified within the scope of the appended claim, without departing from the spirit and scope of the invention. 65

Having thus described the invention, what I claim as new and desire to secure by Letters Patent, is:

As a new article of manufacture, a collar clip comprising inner and intermediate members resiliently connected at their upper ends and adapted to receive and grip a shirt band between them, and an outer member of a substantially greater length than the intermediate and inner member connected to the 70 lower end of the inner member by an expanded loop and adapted with the intermediate member to resiliently grip the collar band, and having its outer face convexly curved transversely to facilitate the slipping of a necktie in the collar and having the inner face of its upper end flared outwardly to hold the collar in spaced relation to the collar band so as to facilitate the entrance of the collar band between the intermediate and outer members, said inner member having its free end extended and curved adjacent the expanded loop to conform thereto so as to prevent the shirt band from slipping when engaged by the inner 85 and intermediate members. 90

CARL E. ZETLITZ.
